UNITED STATES PATENT OFFICE.

A. B. CASS, OF MUSCATINE, IOWA.

IMPROVEMENT IN CULTIVATORS.

Specification forming part of Letters Patent No. 35,668, dated June 24, 1862.

To all whom it may concern:

Be it known that I, A. B. CASS, of Muscatine, in the county of Muscatine and State of Iowa, have invented a new and Improved Corn Plow or Cultivator; and I do hereby declare that the following is a full, clear, and exact description of the same, reference being had to the accompanying drawings, making a part of this specification, in which—

Figure 1 is a sectional side view of my invention, taken in the line $x x$, Fig. 2. Fig. 2 is a plan or top view of the same. Fig. 3 is a front view of the same.

Similar letters of reference indicate corresponding parts in the several figures.

The object of this invention is to obtain a corn plow or cultivator which will admit of having its plows shifted or moved by the driver on his seat, so that the plows may be adjusted with the greatest facility to conform to the sinuosity of the rows, and at the same time admit of being readily raised above the surface of the ground when it is desired to have the implement inoperative, as when being drawn from place to place, turning at the ends of rows, &c.

To enable those skilled in the art to fully understand and construct my invention, I will proceed to describe it.

A represents a rectangular frame, which is mounted on two wheels, B B, and has two shovel-shares, C C, attached to its front part. These shovel-shares have their standards a^* fitted on pivots $a a$ in the frame A, and they are connected at their upper ends by a cross-bar, D, the central part of which is rounded, as shown at b , and has the front end of a lever, E, connected to it. This lever E has a joint, e , at its center, and its back end is attached by a pivot, d , to a lever, F, the lower end of which is fitted within a curved guide, G, attached to the back end of the frame A. The lever F passes up through the driver's seat H, which rests on a slotted curve or segmental support, I, the seat having pendent guides $e e$ attached, which pass through the slot of the support, the latter being attached to inclined bars $f f$ on the frame A. The pendent guides $e e$ are connected by a cross-bar, e^* , through which the lever E passes.

J represent two shovel-shares, the standards $g g$ of which are fitted loosely on a cross-

bar, K, placed transversely in the frame A, and having tenons at its ends which are allowed to turn in the frame. The upper ends of the standards $g g$ are connected by a cross-bar, L, which is attached to the lever E, as shown at h .

The operation is as follows: The driver sits upon the seat H, and as the machine is drawn along the shovel-shares C C smooth or prepare the way for the wheels B B, this being the only function they perform, and to effect such result they are placed directly in front of or in line with the wheels. The shovel-shares J J plow the corn, one being at each side of the row, and the driver by shifting the seat H along on the segmental support I moves the standards $g g$ of said shares on the cross-bar K either to the right or left, as the sinuosity of the row may require, thereby causing the corn to be plowed in a perfect manner. The driver by moving the upper part of the lever F backward by pressing his back against it actuates the lever E and draws back the upper ends of the share-standards, so that the shares will be elevated above the surface of the ground and the implement thereby rendered inoperative. This position of the shares is indicated in red outline in Fig. 1, and the lateral movement of the shares J J is also indicated in red in the same figure. By having the lever E jointed, as shown, the curvilinear movement of the share-standards is compensated for. The lever E is connected to the cross-bar D of the share-standards in such a manner as to admit of the lateral movement referred to.

Thus by this very simple arrangement an efficient corn plow or cultivator is obtained, and one that may be readily operated and be under the complete control of the driver.

Having thus described my invention, what I claim as new, and desire to secure by Letters Patent, is—

The pivoted share standards $a^* a^*$ and sliding share-standards $g g$, connected to the jointed adjustable lever E, in combination with the seat H, and lever F, connected to a lever, E, and the seat-support I, all arranged as and for the purpose specified.

A. B. CASS.
